BY

Edward R. Imman

ATTORNEY.

UNITED STATES PATENT OFFICE.

LLOYD M. DURNEY AND HERBERT J. MONTGOMERY, OF FRANKLIN, PENNSYLVANIA.

DESIGN FOR A SIGNAL FOR AUTOMOBILES.

59,627.

Specification for Design.

Patented Nov. 15, 1921.

Application filed June 29, 1921. Serial No. 481,401. Term of patent 7 years.

To all whom it may concern:

Be it known that we, LLOYD M. DURNEY and HERBERT J. MONTGOMERY, citizens of the United States, residing at Franklin, in the county of Venango and State of Pennsylvania, have invented a new, original, and ornamental Design for a Signal for Automobiles, of which the following is a specification, reference being had to the accompanying drawing, forming a part thereof.

The figure is a front elevation of a signal for automobiles, showing our new design.

We claim:

The ornamental design for a signal for automobiles, as shown.

In testimony whereof we affix our signatures in presence of two witnesses.

LLOYD M. DURNEY.
HERBERT J. MONTGOMERY.

Witnesses:

CLARENCE E. PERRINE,
M. REED HENDERSON.
